UNITED STATES PATENT OFFICE.

SAMUEL H. TACY, OF ELKINS PARK, PENNSYLVANIA, ASSIGNOR TO PRE-HEATED AIR COMPANY, OF PHILADELPHIA, PENNSYLVANIA, A CORPORATION OF DELAWARE.

PREHEATER.

1,193,844.

Specification of Letters Patent. Patented Aug. 8, 1916.

Application filed February 16, 1912. Serial No. 678,076.

To all whom it may concern:

Be it known that I, SAMUEL H. TACY, a citizen of the United States, and a resident of Elkins Park, Pennsylvania, have invented a certain new and useful Preheater, of which the following is a specification.

My invention relates to pre-heaters arranged for engagement with furnace doors, preferably to be supported thereby and swing therewith.

The purpose of my invention is to provide a preferably horizontal frame having air inlet and outlet openings upon the edges toward the door and furnace respectively and having lines of air flow mainly transverse to the length of the pre-heater.

A further purpose of my invention is to provide alternately reversing, transversely directed, communicating air passages progressing from the air inlet at the door end of the pre-heater to the discharge end by successive stages preferably increasing in cross section with each progression.

A further purpose of my invention is to provide a furnace pre-heater with support through its air inlet and with air passages preferably providing greater cross section for the air as its temperature is increased.

A further purpose of my invention is to provide a furnace pre-heater in which differences of cross section are obtained by relatively sloping the outer faces of the pre-heater frame and in which the metal inclosing air passages of larger section is exposed to the greater heat.

Further purposes of my invention will appear in the specification and claims hereof.

I have preferred to illustrate my invention by one form thereof which has proved most practical and efficient and which at the same time well illustrates the theory of my invention.

Figure 1 is a top plan view partly in section of the preferred form of my pre-heater with the top plate removed. Fig. 2 is a vertical section through the middle of the preferred form of my invention in one location of use. Fig. 3 is a vertical section of another form of my pre-heater.

Similar numerals of reference indicate like parts in the specification.

I have preferred to illustrate my invention in use upon a furnace door in which the attachment is simplified by the suitable location of a boss 2 upon the door, so that

the supporting pipe 3 may be screwed into this boss as at 4, providing for air inlet through the end 5. Since my present invention does not concern the restriction or control of the inlet air at the end 5, I have selected a simple form of support, easily available wherever the door is provided with a boss.

Upon the opposite end from the door the pipe 3 is shown as screwed into a boss upon 65 or in the end of the heater frame as at 6, so as to support the heater by its inlet pipe. I prefer to make this end 6 integral with the bottom plate 7 which I show as carrying the partitions 8—14, and to close the 70 upper surface by the plate 15 held in position by any suitable means, as bolts 16. I have selected transverse direction for the passages formed between the walls or partitions 8—14 for the reason that I desire to 75 have the air engage with the edge walls 17, 18 at the points of change of direction, since these edge walls are outside walls and relatively highly heated, increasing the efficiency of the device. I have shown the 80 passages formed successively by these walls 8—14 as of constantly increasing width and correspondingly greater cross section as the air advances to its more highly heated end of the pre-heater and itself increases in 85 temperature.

I have preferred to positively support the pre-heater upon the furnace door by means of the inlet air pipe in order to interfere as little as possible with free access to the fire during the time that the door is open, since the pre-heater may thus be swung entirely free from the heater alley. At the end of the heater nearest the fire, I provide the discharge openings 19 and have 95 arranged for nearly uniform distribution of the air among these openings, by discharging the outgoing warmed air into the final chamber through the opening 20 in wall 14, against baffle plates 21, which are 100 separated by a shorter distance, preferably, than the width of the opening 20.

In the form shown in Fig. 3, I have spaced the partitions for wall 8'—14', uniformly and have provided for increase of 105 cross sectional area as the air progresses toward the discharge end by tapering the frame, causing the top and bottom walls to diverge as they approach the fire. In this form the air in the successive sections re- 110

ceives the greater heating where the depth is greater. Either or both means of changing the section of the passages may be used as well as any other within the scope of my 5 claims.

It will be evident that my device may be quickly and easily attached, preferably rigidly, to the stove door; that it gives direct impact of the air, at the point of reversal of 10 air direction, against the heated side walls of the frame, and that it offers greater extent of engagement with continuous exposed and heated walls, shown as top and bottom walls, or with the ends where reversed, and successively increased cross section of passages from the point of inlet to the point of discharge.

Having thus described my invention, what I claim as new and desire to secure by Letters Patent is:

1. In a device of the character stated, a furnace door, a relatively flat pre-heater frame adapted to be mounted thereon, having outer walls and intermediate partitions 25 arranged transversely to the length of the heater and across it from one face to the other in the direction of its thickness, sides exposed to the heat at the points of change of direction of the hot air currents, each 30 side being spaced from alternate partitions to provide air passages at the sides, and a pipe for mounting the pre-heater within the furnace to swing with the furnace door supplying air to the pre-heater.

2. In a device of the character stated, a pre-heater frame having flat faces and inlet discharge openings, connecting partition members transverse to the length of the heater embracing successively increased

cross sections from the point of air inlet to 40 the point of discharge, and sides exposed to the heat of the furnace, against which the air is turned in its progression from one transverse passage to another and a pipe mount therefor adapted to supply air to the 45 section of least cross sectional area.

3. In a device of the character stated, top and bottom pre-heater walls, intermediate partitions embracing substantially rectangular areas of successively increasing cross 50 sections and edge walls, in combination with an inlet connection and an end wall having spaced apertures, and spaced baffle plates sloping with respect to the partitions and distributing the air among these apertures. 55

4. In a device of the character stated, a pre-heater frame of relatively flat form having substantially parallel faces and inlet and discharge openings, connecting partition members transverse to the length of 60 the heater, alternate partitions terminating at a distance from opposite sides of the frame to provide longitudinal passages connecting the spaces between the partitions, the partitions being spaced progressively 65 different distances apart from the inlet toward the point of discharge and sides exposed to the heat of the furnace against which the air is turned in its progression from one transverse passage formed to another in combination with an inlet air pipe for the pre-heater, which pipe also forms the support for it. 70
